UNITED STATES PATENT OFFICE.

JOHN C. MCINTOSH, OF GRAYMONT, ILLINOIS, ASSIGNOR OF ONE-HALF TO
ALBERT MEIERHOFER, OF MINONK, ILLINOIS.

APPARATUS FOR LOADING GRAIN-CARS.

SPECIFICATION forming part of Letters Patent No. 634,122, dated October 3, 1899.

Application filed December 22, 1898. Serial No. 700,015. (No model.)

To all whom it may concern:

Be it known that I, JOHN C. MCINTOSH, a citizen of the United States, residing at Graymont, in the county of Livingston and State 5 of Illinois, have invented a new and useful Apparatus for Loading Grain-Cars, of which the following is a specification.

My invention relates to improvements in apparatus for handling grain for the purpose 10 of transferring it from an elevator-building to a grain-car, and the primary purpose is to provide an apparatus of simple construction by which the grain may be thrown or distributed toward one or both ends of a car 15 and effect the operation known as "trimming" a car.

A further object of the invention is to provide an apparatus which may be adjusted to project its working elements well into a grain- 20 car for the purpose of bringing the distributor to a position proper to deliver the grain, and said working elements may also be adjusted to withdraw them from the car previous to moving the apparatus to another 25 spout of the elevator-building or placing another car in position to be loaded by the apparatus.

Further objects of the invention are to provide the loading apparatus with means by 30 which the rotary centrifugal distributor may be propelled positively in each of its several adjusted positions, to provide a cut-off mechanism for controlling the delivery of grain in one or both directions from the rotary distributor, to provide means for adjusting the distributor and causing the delivery-spout thereof to face in different directions toward the end of a car, and to provide a regulator mechanism for controlling the quantity of 35 grain that flows to the revolute distributor. 40

With these ends in view the invention consists in the novel combination of mechanisms and in the construction and arrangement of parts, which will be hereinafter fully described and claimed.

To enable others to understand the invention, I have illustrated the preferred embodiment thereof in the accompanying drawings, forming a part of this specification, and in 45 which—

Figure 1 is a sectional plan view of a por-

tion of an elevator-building and a grain-car, showing my loading apparatus in operative relation thereto. Fig. 2 is a vertical sectional elevation through the structure represented 55 by Fig. 1. Fig. 3 is a longitudinal sectional view taken through the loader apparatus disconnected from a building and a grain-car. Fig. 4 is a horizontal sectional view through the distributor on the plane indicated by the 60 dotted line 4 4 of Fig. 3. Fig. 5 is a vertical transverse section through the distributor on the line 5 5 of Fig. 4. Fig. 6 is a detail perspective view of one of the brackets by which the loader apparatus may be in part supported on an elevator-building. 65

Like numerals of reference denote like and corresponding parts in each of the several figures of the drawings.

The loading apparatus of my invention is 70 designed to span the space between an elevator-building and a grain-car, and this loading apparatus embraces as one element thereof a revolute distributor which is designed to be supplied with grain from the elevator- 75 building and is driven positively by suitable gear connections with the line-shaft mounted on the elevator-building for the purpose of acting on the grain centrifugally to throw the grain toward one or both ends of a car. An 80 apparatus of this character should provide for the adjustment of the distributor mechanism into a car to bring said distributor mechanism in a position proper for loading the grain into the ends of the car, and said 85 distributor mechanism should also be retracted or withdrawn from a car readily for the purpose of bringing another car into position to be loaded or of conveniently adjusting the loader apparatus from one spout to another 90 of the elevator-building. The apparatus, which I now proceed to describe, is especially designed to fulfil the conditions and to carry out the objects hereinbefore enumerated.

The base-frame 10 is of substantial light 95 construction to carry the working elements of my loader apparatus, and this frame is constructed to provide a longitudinal track or way 11, which accommodates a slideable carrier-frame 12. This carrier-frame is superposed upon the base-frame, and it is confined 100 by the track or way 11 and by the fixed guides

13 to endwise-slidable movement on the base-frame, whereby the carrier-frame may be projected in one direction from the base-frame, or it may be drawn inwardly to lie within the limits of the base-frame. The guides 13 are fastened firmly to the base-frame and embrace the carrier-frame to hold the latter against vertical displacement; but the particular construction of the guides is not important. The slidable carrier-frame is provided with journal-bearings 14, which are arranged in alignment with each other longitudinally of said frame 12, and in these bearings is mounted a longitudinal driving-shaft 15, which is thus connected with the frame 12 to partake of its endwise adjustment and at the same time be free to rotate in its bearings for the propulsion of the rotary distributor. The rotary distributor mechanism is mounted on the slidable carrier-frame 12, at or near one end thereof, and this distributor mechanism is thus made adjustable with the carrier-frame, so that on the projection of the latter beyond the base-frame the distributor mechanism may be positioned within a car for the purpose of throwing the grain toward one or both ends of the car. The distributor mechanism embraces a casing and a revolute head provided with wings or blades, said head arranged to operate within the casing to which the grain is fed or supplied from one of the spouts of the elevator-building. The revolute distributor-head is geared to the driving-shaft 15 to be rotated thereby, and as the distributor and the shaft 15 are mounted on the carrier-frame 12 for adjustment therewith the distributor may be driven by the shaft 15 at any point of its adjustment within a car. The casing of the distributor mechanism is fastened securely to a horizontal base-plate 16, preferably of metal and provided with laterally-extended wings 17, which are out of line with each other. The casing 18 of the distributor may be made of sheet metal of substantially annular form and secured firmly to the base-plate 16, and this distributor-casing is formed with spouts 19 20, which extend from opposite sides of the casing outwardly therefrom and arranged out of line with each other, so as to lie over the wings 17 of the base-plate 16. The wings form the bottoms of the spouts 19 20, and these spouts face in opposite directions from the center of the distributor-casing. Said base-plate 16 and the distributor-casing are mounted or fitted on the carrier-frame 12 to assume a position transversely to the longitudinal axis of the carrier and base frames 12-10, and as the loader apparatus stands in a position at right angles to the position of the car the distributor is adapted to assume a position when the carrier-frame is projected through the car-door in which the spouts 19 20 face toward opposite ends of the car. The shell of the distributor-casing 18 is extended upwardly a proper distance to provide a hopper 21, and within the distributor-casing 18

is secured a transverse horizontal plate 22, which constitutes the bottom to the hopper-chamber. This horizontal plate 22 is secured firmly in place to the casing 18, and it is provided with wings 23, which fit in the spouts 19 20 in parallel relation to the wings 17 on the base-plate 16, whereby the spouts are formed by and between the wings 17 23 of the plates 16 22 and the extensions 19 20 of the distributor-casing. The plates 16 22 and the annular portion of the casing 18 provide a chamber within which is fitted a horizontal revolute head 24, which is preferably in the form of a metallic disk arranged in compact relation to the base-plate 16. This revolute head is provided on its upper side or face with a series of radial blades 25, which are secured firmly to said head and project upwardly therefrom, and this head is revolute in the horizontal plane of the oppositely-facing spouts 19 20 of the distributor-casing, whereby the head is adapted to throw the grain by centrifugal action through one or both of the spouts 19 20, and thereby impel the grain toward one or both ends of the car. The revolute head 24 is carried by a vertical shaft 26, which is secured firmly to the head and passes loosely through an opening 27, provided centrally in the base-plate 16, said shaft being journaled at a point intermediate of its length in a journal-bearing 28, which is secured firmly to the carrier-frame 12. The lower end of the vertical shaft which carries the revolute head protrudes below the bearing 28 to receive a bevel-gear pinion 29, which meshes with a driving-gear 30, which is fixed to one end of the horizontal shaft 15, and the intermeshing bevel-gears are thus adapted to transmit the motion of the shaft 15 to the shaft 26 for the purpose of rotating the head 24 at high speed to insure the proper operation of said head in distributing the grain.

The horizontal upper plate 22 is provided with two or more ports or opening 31 32, which are disposed on opposite sides of the vertical axis of the distributor-casing, and these openings or ports establish communication between the hopper 21 and the chamber which contains the revolute head 24. By locating the openings as described the grain is adapted to pass from the hopper and lodge upon the revolute head at points outside of the vertical axis thereof, whereby the blades 25 of said revolute head are caused to act on the grain and impel the latter through the casing-spouts 19 20. To regulate the quantity of grain which may pass from the hopper to the revolute distributor, I provide the slides 33, which are fitted upon the upper plate 22 in positions to move across the openings 31 32, and each slide is confined within a guideway 34 on the upper plate 22. It is evident that both slides may be adjusted to open or close the openings 31 32, or said slides may be partially adjusted over the openings in order to have the grain pass through

the openings, and thus admit a restricted quantity of grain to the chamber within which operates the revoluble head. Under some conditions in the service of the apparatus it is not desirable to have the revoluble head distribute the grain through both spouts 19 20 toward opposite ends of the car, and to cut off the grain impelled by the distributor from passing through both spouts at one operation. The cut-offs 35 are placed in the spouts 19 20 out of the path of the revoluble distributor. Each cut-off is hinged or connected at 36 to the spout in a manner to drop or fold down compactly against the bottom wing 17 thereof, and the spout cut-off may be raised to an inclined position by means of an adjusting-lever 37, which is fitted in a slot 38 in the wing 17 and is fulcrumed at 39 to said wing. The upper working end of the adjusting-lever is beveled, so that when it is moved to one position its beveled end will lie substantially flush with the edge of the slot 38 in the wing 17 and allow the cut-off 35 to drop or fall by gravity, thus opening the passage to the spout for the free egress of the grain. A reversal in the adjustment of the lever brings its beveled working end into contact with the movable cut-off 35 to elevate the latter and close the passage through the spout, thus preventing the egress of grain at one side of the casing 18. It is evident that the cut-offs may be operated independently of each other for the purpose of distributing the grain toward either end of the car; but under ordinary conditions both of the cut-offs should be opened for the revoluble distributor to throw the grain toward both ends of the car.

It will be noted that the casing, its top plate, and the hopper are attached to the base-plate 16, which rests upon the carrier-frame, and in order to insure uniformity in the distribution of the grain from side to side of the car I have provided means for adjusting the distributor-casing, so that the horizontal axis of said casing may be changed to different angles with respect to the longitudinal axial line of the car, whereby the positions of the spouts 19 20 of the said distributor-casing may be changed to deliver the grain across the ends 50 of the car, and thus secure uniformity in the distribution or trimming of the grain. This end is attained by fitting the base-plate 16 loosely on the vertical shaft 26, which carries the revoluble head, and by providing an adjusting device which is connected with the casing, so that it may be shifted bodily to change the position of its spouts with reference to the axis of the car, the axis of adjustment of the distributor-casing being concentric with the axis of the shaft 26 and the head 24, so that the revoluble head may rotate freely within the casing at all points of its adjustment. The adjusting-rod 40 is shown as attached to the base-plate 16, which is loosely fitted around the shaft 26, and this adjusting-rod extends longitudinally of the carrier-frame to bring its free end into posi-

tion convenient for manipulation by an attendant and to enable said end to be engaged with one of a series of stop-pins 41 or 70 other detent for the purpose of holding the casing to its adjusted position.

The base-frame 10 of my apparatus is designed to be supported at one end on an elevator-building in a position below and contiguous to the grain-spouts thereof, and as one means for supporting this frame on the building I have provided a series of hinge-brackets constructed in sections and fastened, respectively, to the base-frame 10 and a wall 75 of the elevator-building 45. The end of the base-frame 10 which is next to the elevator-building has short vertical posts 42, secured firmly thereto, and to these posts are fastened the hinge-brackets 43. A series of 80 hinge-brackets 44 are fastened to the elevator-building 45 in the same horizontal plane and contiguous to the spouts thereof, and the brackets 44 are spaced in pairs on the elevator-building to correspond to the spacing 85 of the brackets 43 on the loader-frame. The loader-frame may be adjusted to bring its pair of brackets 43 coincident with either of the pairs of brackets 44 on the building, and said brackets may be connected detachably 90 together by the removable hinge-bolts 46, which pass vertically through the coincident brackets 43 44 to detachably fasten the loader-frame on the building. This loader-frame may be detached from one pair of brackets 95 44, which lie adjacent to one spout, and shifted to another pair of brackets adjacent to another spout of the elevator-building, thus providing for adjustment of the loader bodily from one spout to another. For the 100 purpose of swinging the loader mechanism out of the path of the car one of the hinge-bolts 46 may be removed, while the other hinge-bolt remains in place to pivotally attach the loader at one corner to the building, 105 and the loader mechanism may thus be swung in a horizontal plane to a position alongside of the elevator-building.

For the purpose of propelling the driving-shaft 15 at all points of adjustment of the 110 loader adjustment of the building and in operative relation to each of the spouts therein I provide a line-shaft 47, which is journaled in suitable bearings in the building 45 and is adapted to be rotated by mechanism within 115 the elevator-building—as, for instance, by one of the elevators thereof. This line-shaft is equipped with a series of gear elements 48, which are adapted to be connected by gearing, as 49, to the shaft 15, and thus the shaft 120 125 may be driven from the line-shaft when the loader mechanism is in proper position within a car. The car 50 may be of any ordinary pattern, and in Figs. 1 and 2 it is shown as having a door 51 in one side thereof.

The operation may be described as follows: The car to be loaded having been run alongside of the building the loader mechanism is adjusted on the building adjacent to one of

the spouts and opposite to the door 51 in the car. The loader-frame 10 is supported by the brackets on the building, and the carrier-frame 12 is projected through the car-door 51, so as to adjust the distributor to a substantially central position within the car and for its spouts 19 or 20 to face in opposite directions toward the ends of the car. The gearing 48 is now adjusted to connect the shaft 15 with the line-shaft 47, and a spout or other conduit 53 is led from one of the elevator-spouts to the hopper 21 of the distributor. The rotary distributor is propelled by the train of gearing between its shaft 26 and the line-shaft and the grain is conveyed from the elevator-spout to the hopper. One or both of the slides 33 are adjusted to expose the openings 31 32, and the grain passes from the hopper to these openings to lodge upon the revoluble head 24, the blades of which throw the grain by centrifugal force through the spouts 19 20 toward the ends of the car. It is evident that one of the slides 33 may be adjusted to close one port or opening and that one cut-off 35 may be raised to close one spout, thus forcing the grain to one end of the car. For the purpose of distributing the grain uniformly to either or both ends of the car, and thereby trim the car, the rod 40 may be adjusted to shift the position of the distributor-casing and vary the angle of the spouts 19 20 to the axis of the car, and as the casing may be adjusted a number of times it is evident that the grain thrown by the rotary distributor may be distributed from side to side of the car, thus insuring uniform loading of the car at both ends thereof. The loader mechanism may be removed bodily from one elevator-spout to another by taking out the hinge-bolts 46, changing the position of the loader-frame, and replacing the bolts, or the loader-frame may be swung on one bolt as the pivot horizontally alongside of the building. To remove the loader from the car, the carrier-frame 12 is moved endwise on the base-frame 10 in order to lie within the limits of the base-frame and bring the distributor to a position immediately over said base-frame. The distributor is thus withdrawn from the car for the purpose of compactly disposing the parts previous to shifting the position of the loader, and a filled car may be moved from a position opposite the loader to enable an empty car to be drawn into position to receive grain from the loader mechanism.

In Figs. 1 and 2 of the drawings the loader-frame is shown as resting on a track or shelf 52, which preferably is screwed to the side of the elevator-building. This track extends horizontally below and parallel to the line-shaft for the inner part of the loader-frame to rest thereon, and said track relieves the hinge or attaching-brackets from undue strain. The loader-frame is adapted to slide or travel on the track from one pair of brackets to the other. As the distributing mechanism is mounted on the extensible part of

the loader-frame, and as the driving-shaft 15 for the distributor must remain in gear with the shaft 26 and the line-shaft, I make the shaft 15 extensible or telescopic at 15^a and 15^b for the purpose of lengthening or shortening the same according as the slidable or extensible frame is moved outward from or inward toward the line-shaft. Of course the parts of the telescopic shaft should be keyed or so fitted together as to enable them to rotate together and permit the slidable movement.

Changes may be made in the form and proportion of some of the parts, while their essential features are retained and the spirit of the invention embodied. Hence I do not desire to be limited to the precise form of all the parts as shown, reserving the right to vary therefrom.

What I claim is—

1. In a grain-loader, the combination with a line-shaft, of a carrying-frame, means for supporting said frame in shiftable relation to said shaft to occupy different positions along the length thereof, a distributor mechanism on said frame, a shaft supported by the frame and geared to the line-shaft and to a movable element of the distributor mechanism, and means for supplying grain to said distributor mechanism, substantially as described.

2. In a grain-loader, the combination with a line-shaft, of an extensible carrying-frame, means for supporting one member of said frame in shiftable relation to said line-shaft, a distributor mechanism carried by the movable element of the extensible frame, and an extensible shaft mounted on said frame to be extensible therewith and for its members to be geared respectively to the line-shaft and to a movable element of the distributor mechanism, substantially as described.

3. In a grain-loader, the combination with a line-shaft, of a carrying-frame, means for pivotally supporting said frame with relation to the line-shaft for the frame to be adjusted laterally, a distributor mechanism on said frame, and a shaft journaled on the frame and geared to the line-shaft and to an element of the distributor mechanism, substantially as described.

4. In a grain-loader, the combination of an adjustable carrier-frame, a shiftable casing mounted on said frame to be adjustable therewith and provided with oppositely-facing spouts, a revoluble head within said casing, and means for shifting the position of the casing independently of the adjustment of the carrier-frame or the rotary motion of the head, substantially as described.

5. In a grain-loader, the combination with a supporting-frame, of a carrier-frame slidably fitted to the supporting-frame, a distributor mechanism mounted on one end of the carrier-frame to be adjustable therewith and having a rotary head housed within the casing, a line-shaft, and an extensible shaft mounted on the respective frames and geared

to the line-shaft and to the rotary head of said distributor mechanism, substantially as described.

6. In a grain-loader, the combination with 5 a supporting-frame, of a carrier-frame slidably fitted to said supporting-frame, a distributor mechanism mounted on the carrier-frame and comprising a rotary head and a shiftable casing, said casing being provided with 10 oppositely-facing valved spouts, means for positively driving the rotary head, and an adjusting device connected operatively with the distributor-casing for shifting the latter independently of the adjustment of the carrier-frame or the rotary motion of the distributor-head, substantially as described.

7. In an apparatus for handling grain, the combination of a casing provided with oppositely-facing spouts, a revolute head within 20 said casing, and independent cut-offs in operative relation to the spouts of said casing, substantially as described.

8. In an apparatus for handling grain, the combination of a revolute head, a casing enclosing 25 said head and provided with oppositely-facing spouts, and independent cut-offs supported within said spouts and each controlled by an adjusting-lever, substantially as described.

30 9. In a grain-loader, the combination of a casing provided with the oppositely-facing spouts and with the spaced feed-ports in the head thereof, a hopper to supply the grain to said casing, independent cut-offs in the spouts 35 of the casing, and a revolute head mounted within the casing to act on the grain delivered thereto by the feed-ports, substantially as described.

10. In an apparatus for handling grain, the 40 combination of a casing provided with a hopper and with oppositely-facing spouts, an upper plate between a chamber of the casing and said hopper and said plate provided with spaced openings, independent slides mounted 45 on the plate for adjustment across the openings therein, and a revolute head supported within the casing, substantially as described.

11. In a grain-loader, the combination of a casing provided in its upper side or head with 50 spaced feed-openings and having the laterally-extended spouts, the independent cut-offs in said spouts of the casing, levers for adjusting the cut-offs, a distributor-head revolute within the casing below the feed-openings 55 therein and provided with offstanding blades to act on the grain centrifugally, and regulating-slides to traverse the feed-openings, substantially as described.

12. In an apparatus for handling grain, the 60 combination with a supporting-frame and a

carrier-frame fitted adjustably thereto, of a distributor mechanism mounted on the carrier-frame and comprising a shiftable casing, a revolute head within said casing, a driving device for said head and mounted on the carrier-frame, and an adjusting device connected with the shiftable casing and adapted for engagement with the carrier-frame, said casing being shiftable independently of any adjustment of the carrier-frame or the rotary motion of the head, substantially as described.

65 13. In an apparatus for handling grain, the combination with a series of fixed brackets adjacent to spouts of an elevator-building, of a loader mechanism, brackets attached to said loader mechanism and shiftable therewith in operative relation to certain of the fixed brackets, and connecting-bolts detachably fitted to the loader-mechanism brackets and to certain of the series of fixed brackets, substantially as described.

70 14. In a grain-loader, the combination of a casing provided with the delivery-spouts which are extended from opposite sides thereof, a revolute head housed within said casing, driving mechanism for positively rotating the head in a horizontal plane, and means for adjusting said casing, the casing and its spouts being shiftable in a horizontal plane 85 relatively to the vertical axis of the distributor-head, substantially as described.

75 15. In a grain-loader, the combination with a line-shaft, of a carrying-frame shiftable with relation to said shaft to occupy different positions along the length thereof, a distributor-casing pivotally mounted on said frame and movable therewith in its shiftable adjustments, a feed-chute arranged to deliver to the distributing-casing, a revolute head within 95 said casing, a shaft geared to the line-shaft and to said head, and means for shifting the distributor-casing for its discharge-spout to occupy different positions relatively to the axis of said frame, substantially as described.

80 16. In a grain-loader, the combination of an extensible frame, a distributor mechanism carried by the movable element of said frame, a line-shaft, and a telescopic shaft geared to the line-shaft and to a revolute element of 100 said distributor mechanism, said telescopic shaft being extensible with said frame, substantially as described.

85 In testimony that I claim the foregoing as my own I have hereto affixed my signature in the presence of two witnesses.

JOHN C. MCINTOSH.
